CLAIM

The ornamental design for a tapered beverage container sleeve, as shown and described.

DESCRIPTION

FIG. 1 is an oblique view of a tapered beverage container sleeve showing my new design.

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The lettering and other broken lines of FIGS. 1–5 depict markings on the tapered beverage container sleeve that form no part of the claimed design.
